J. J. FISHER.
RADIATOR.

No. 20,131.

Fig. 2. Patented Sept. 2, 1890

UNITED STATES PATENT OFFICE.

JOHN J. FISHER, OF ALLEN TOWN, PENNSYLVANIA.

DESIGN FOR A RADIATOR.

SPECIFICATION forming part of Design No. 20,131, dated September 2, 1890.

Application filed August 7, 1890. Serial No. 361,398. Term of patent 14 years.

To all whom it may concern:

Be it known that I, JOHN J. FISHER, a citizen of the United States, residing at Allentown, in the county of Lehigh, State of Pennsylvania, have invented and produced a new and original Design for Radiators, of which the following is a specification, reference being had therein to the accompanying drawings.

Figure 1 is a side elevation showing my design. Fig. 2 is a top plan, and Fig. 3 is a side elevation of one of the supports.

The leading feature of my design consists in the alternately-arranged ornamentations upon the radiator tubes or pipes, with the rosettes between the ends of each two tubes or pipes at their junction with the base and cap.

A designates the tubes; B, the base, and C an overhanging top, which is of the open-work design, as seen in Fig. 2.

The ornaments D upon the tubes are alternately arranged, as seen in Fig. 1, and consist of the representation of a vine with alternately-arranged scrolls formed by a branched and main vine, each branch terminating in a leaf within the scroll.

E are rosettes arranged at the top and bottom opposite the space between each two tubes or plates, as seen in Fig. 1.

What I claim is—

The design for a radiator, substantially as herein shown and described.

In testimony whereof I affix my signature in presence of two witnesses.

JOHN J. FISHER.

Witnesses:

EDWARD RUHE,
EDWARD X. RENINGER.
